UNITED STATES PATENT OFFICE

HARLEY J. EARL AND JOHN F. WILSON, OF DETROIT, MICHIGAN, ASSIGNORS TO GENERAL MOTORS CORPORATION, OF DETROIT, MICHIGAN, A CORPORATION OF DELAWARE

FRONT SPLASH GUARD WITH COVERED CRANK HOLE

Application filed July 3, 1929. Serial No. 375,782.

It is a primary object of this invention (1) to improve the appearance of the forward end of an automotive vehicle by means involving the use of a novel guard element; and, in preferred embodiments of this invention, the foregoing object may be so attained as not only (2) to aid in avoidance of splash upon exposed forward parts but (3) to provide harmonious arrangements of lustrous border or trimming elements, curved surfaces and lines, (4) to facilitate the attachment and support of adjacent fenders, bumpers and radiators, and (5) to permit the insertion of a starting crank without removal of said guard element, by providing therein a special opening which may be normally closed or concealed by a forwardly-extending decorative device hereinafter described.

Even though the mentioned guard element and associated parts may be formed of materials which are too light or are unfavorably shaped for any important contribution to structural rigidity, a forward inclination of the mentioned guard element or plate may be favorable to (6) enhancement of the draft of air through a radiator disposed thereabove—said radiator being preferably trimmed in harmony with the splash device and optionally partially concealed by the mentioned guard element; and, to impart desired strength to said guard element, it may be (7) provided with a depressed area, with hidden or other reinforcements and/or with any desired corrugations or louvers.

Other objects of the present invention may be best appreciated from the following description of an illustrative embodiment thereof, taken in connection with the appended claims and the accompanying drawings.

Fig. 1 is a somewhat conventional front elevational view in which a bumper is shown as broken away to exposed parts which are included in or carried by the novel splash guard; and a harmonious decorative element which is optionally provided at the edge of a radiator shell thereabove, and parts of the mentioned bumper which are also harmoniously related to parts of the present invention, are shown in heavier lines than those

parts which are entirely immaterial to the present invention.

Figs. 2 and 3 are respectively vertical sectional views, on a larger scale and with parts broken away or omitted, taken substantially as indicated by the lines 2—2 and 3—3, an unimportant optional feature of modification being suggested in Fig. 2.

Fig. 4 is a top plan view, with parts eliminated.

Fig. 5 is a vertical sectional view, taken substantially as suggested by the line 5—5 of Fig. 4.

Figs. 6 and 7 are enlarged detail views taken substantially as indicated by the lines 6—6 and 7—7 of Fig. 4.

Fig. 8 is a vertical sectional view, upon an intermediate scale, taken substantially as indicated by the line 8—8 of Fig. 3, but with parts broken away.

Referring first to parts which are externally visible and which are shown in Figs. 1—3 inclusive, a vehicle comprising a special or usual body 11, fenders 12, 12', an axle 13, wheels 14, 14' and a radiator shell 15 at the front of a hood 16 may include also a usual or special chassis comprising so-called spring-attachment "horns" 17, 17'. These horns are shown as carrying a bumper 18 (preferably so held by clips 19 as to obviate all use of brackets) and as practically concealed from view by a novel splash guard organization 20 illustrative of the present invention.

A central element of this novel guard organization may take the form of a forwardly rounded and downwardly inclined apron or plate 21, providing a comparatively large depressed area which lies below the top surface of the "horns" and is surrounded on three sides by upstanding ledges 22, 22', 22''. The total breadth of this plate 21 may be somewhat less than the distance between horn 17, 17'; and support of said plate from said horns may be effected by the use of a pair of suitable horn-concealing "wing" elements 23, 23'. These are preferably formed separate and may be used with or without a pair of flanged side plates or other web or fin elements 24, 24', optionally vertical and em-

ployed for a splash receiving and/or a reinforcing effect.

To contribute to the strength of the depressed portion of the plate 21 and/or to provide for a decorative effect harmonious with the horizontal lines of the bumper 18, or its equivalent, said plate may be provided with any desired number of horizontal or other sets of corrugations 25; and an otherwise unbroken central area 26 of said plate may also be provided with an opening adapted to permit the use of an engine-starting crank,—said opening being preferably provided with or concealed by a decorative cap or other closure device or organization 27.

As illustrated, in Figs. 3, 4 and 8, the closure device 27 may comprise a substantially cylindrical or tubular portion 28, adapted downwardly to engage up-turned flanges 29, 29', provided at the edge of an elongated opening 30 in the central area 26 of plate 21. The rearward or inner end 31 of this cylindrical element may, whether or not said cylindrical element is intended to be bodily removable, be provided with a lug or finger 32, engageable under the plate 21; and the forward end of the cylindrical element 28, or its equivalent, may be provided with releasable retaining means such as a spring catch 33, shown as riveted at 34 to a substantially vertical element front 35, integral with the mentioned cylindrical body, and as provided with a finger piece 36. An inward or rearward movement of this finger piece 35 may so disengage said catch from beneath a substantially straight transverse edge 37, provided at the front of the opening 30, as to permit bodily removal of the entire closure organization 27,—in case a mere upward pull on the forward end of tubular element 28 is without effect.

It will be understood that the described provision for bodily removal of the device 27 obviates all necessity for the provision of any crank-passing opening in the front thereof; and said closure organization may accordingly include either a removable cap or a purely decorative circular element 38, optionally simulating a chromium plated cap, at the forward end thereof. In Fig. 8, the mentioned cap or decorative element 38 is shown as provided with three inwardly-extending lugs 39, projecting through corresponding openings 40 in the vertical element 35; and the shape of the openings 40 may naturally depend upon whether or not a permanent connection, rather than a so-called bayonet joint, or the like, is desired at this point.

Referring now more particularly to Figs. 4-7, the last-mentioned figure is provided mainly to illustrate the possibility of providing some or all of the corrugations 25 with downwardly-inclined drainage or dust-passing openings 41, serving as louvers in the

plate 21; and Figs. 5 and 6 clearly illustrate a preferred method of inter-connecting marginal flanges 42, 43 and 44, preferably provided respectively by over-lapping portions of the ledges 22, 22', at the edges of plate 21, by adjacent and inwardly sloping portions 45 of the wings 23, 23', and by parallel flange elements 46, integral with the vertical or other reenforcing web elements 24, 24'.

The over-lapping flanges 42, 43 and 44 may be held in their indicated assembled relationship by spaced means such as a series of rivets 47, preferably concealed by novel means such as strips 48, 48' of chromium plated sheet metal or other lustrous or other decorative material, secured thereabove,—as by means of bolts 49, concealed therein and extending through slots or other openings 50 provided in the mentioned over-lapping flanges. The heads of the mentioned bolts 49 may be adapted to engage inwardly-extending flanges 51, 51', integral with the strips 48; said bolts may be provided as at 52, with noncircular shoulders adapted to prevent rotation thereof during the tightening of nuts 53 thereon; and, whether or not the respective wing elements 23, 23' are outwardly provided with means such as down-turned flanges 54, adapted to fit over the "horns" 17, 17' and/or suitably bent edges 55 of the fender elements 12, 12', said wing elements 23, 23' may be retained not only by perfection of fit but by a clamping engagement between said "horns" and the bases 56, 56' of light-carrying posts 57, 57', or the like. For the purpose last referred to, the wings 23, 23' are shown as provided with spaced openings 58, 58', suitable for the reception of screws or bolts employed in the attachment of the brackets 56, 56'; and an alternative or additional securing effect may be obtained by the use of suitably formed bumper-retaining clips 59, by bolts 60 for the attachment and tightening of the same and/or by means such as an inwardly-extending horizontal ledge 61, shown as integral with the plate 21 and as engaged by a bottom element 62 of the radiator shell 15.

The splash-obviating advantages of the described organization being evident upon inspection, the mechanical merits of mentioned features, including the opening 30 and the closure element therefor have been fully indicated in connection with the foregoing description; but attention may again be directed, in conclusion, to the improvements in appearance which result from the use of a splash organization which not only covers the horns 17, 17' but practically fills the space therebetween; and the attractiveness of this organization is enhanced not only by the mentioned parallelism of horizontal lines provided by the corrugations or louvers 25 and bumper 18, if the latter is provided, but also by an optical continuity of the decorative

strips 48, 48' (which conceal the joint between mentioned sheet-metal elements such as the plate 21, the wings 23, 23' and the fins 24, 24'—hiding any weld spots or rivets 47) with similarly rounded lustrous elements 63, 63', shown as laterally bordering the front face of the radiator shell 15, these being preferably of similar curvature and plated similarly to said strips.

10 The net result is structurally satisfactory, even though the materials of the mentioned parts be too light to make any important contribution to the rigidity of the chassis; the organization is adapted to be completely preassembled and to be easily and quickly applied without the use of a single bolt, screw or other fastening element additional to those referred to or otherwise required; mentioned decorative features contribute substantially to the sale of cars; and described features of 20 plate 21 are not only favorable to subsequent cleanliness but to an appreciable upward deflection and enhanced circulation of air through the radiator thereabove.

25 Although the foregoing description has included details of but a single embodiment of the present invention, attention may be called, in conclusion, to the facility with which one or more of the mentioned sheet 30 elements may be so formed or extended as to provide a complete receptacular unit accessible through the opening 30,—the exact configuration of reinforcing convexities and/or 35 conical curvatures such as are suggested at 64 and 65 in Figs. 2 and 5, being relatively immaterial.

We claim:

1. In a splash guard organization: a forwardly inclined and laterally flanged apron 40 element comprising a depressed area having less lateral breadth than the distance between chassis horn elements extending forwardly of a radiator shell; and a pair of flanged horn-concealing wing elements respectively provided with flanges at opposite sides thereof, the inner flanges thereof being secured to flanges upon said apron.

2. In a splash guard organization: a forwardly inclined and laterally flanged apron 50 element comprising a depressed area having less lateral breadth than the distance between chassis horn elements extending forwardly of a radiator shell; and a pair of flanged horn-concealing wing elements respectively provided with flanges, the inner flanges thereof being secured to flanges upon said apron by substantially parallel joints; and decorative means for concealing said joints.

60 3. A splash guard organization: a forwardly inclined and laterally flanged apron element comprising a depressed area having less lateral breadth than the distance between chassis horn elements extending forwardly 65 of a radiator shell; and a pair of flanged horn-concealing wing elements respectively

provided with flanges, the inner flanges thereof being secured to flanges upon said apron: and substantially vertical plate elements provided under the said apron.

4. In a splash guard organization: a forwardly inclined and laterally flanged apron 70 element comprising a depressed area having less lateral breadth than the distance between chassis horn elements extending forwardly of a radiator shell; and a pair of flanged horn-concealing wing elements respectively provided with inner flanges secured to flanges upon said apron; and flanged side plate elements provided under the respective lateral flanges of said apron,—all of said elements 75 so being secured together by means uniting overlapping flanges thereof.

5. In a splash guard organization: a forwardly inclined and laterally flanged apron 80 element comprising a depressed area having less lateral breadth than the distance between chassis horn elements extending forwardly of a radiator shell; and a pair of flanged horn-concealing wing elements respectively provided with flanges at opposite sides thereof,—the inner flanges thereof being secured to flanges upon said apron, and joints between said elements being concealed by decorative means extending longitudinally of 85 said joints.

6. In a splash guard organization: a forwardly inclined and laterally flanged apron 90 element comprising a depressed area having less lateral breadth than the distance between chassis horn elements extending forwardly of a radiator shell; and a pair of flanged horn-concealing wing elements respectively provided with flanges at opposite sides thereof,—the inner flanges thereof being secured to flanges upon said apron by joints; strips, 95 thereover, provided with inturned flanges; and bolts whose heads engage said flanges.

7. In a splash guard organization: a forwardly inclined and laterally flanged apron 100 element having less lateral breadth than the distance between chassis horn elements extending forwardly of a radiator shell; and a pair of flanged horn-concealing wing elements respectively provided with flanges, inner 105 flanges thereof being secured to said apron and joints between said elements being concealed by lustrous metallic strips providing channels; and concealed bolts whereby said strips are retained.

In testimony whereof we affix our signatures.

HARLEY J. EARL.
JOHN F. WILSON.
